(57) **CLAIM**

The ornamental design for a secure private server, as shown and described.

DESCRIPTION

FIG. 1 shows a perspective view of a secure private server; FIG. 2 shows a front view of the secure private server of FIG. 1;

FIG. 3 shows a back view of the secure private server of FIG. 1;

FIG. 4 shows a left side view of the secure private server of FIG. 1;

FIG. 5 shows a right side view of the secure private server of FIG. 1;

FIG. 6 shows a top view of the secure private server of FIG. 1; and,

FIG. 7 shows a bottom view of the secure private server of FIG. 1.

The broken lines represent portions of a secure private server that form no part of the claimed design.
